ATTORNEY

UNITED STATES PATENT OFFICE.

GEORGE M. SCHMIDT, OF CEDAR RAPIDS, IOWA.

AWNNG PROTECTOR.

Application filed May 10, 1926. Serial No. 108,134.

This invention relates to an awning support, the general object of the invention being in the awning by changing their position of the central awning supporting rolls, 5 so as to prevent the rolls from wearing holes in the awning by changing their position to bring a new part of the awning in contact with the rolls.

This invention also consists in certain other 10 features of construction and in the combination and arrangement of the several parts, to be hereinafter fully described, illustrated in the accompanying drawings and specifically pointed out in the appended claim.

15 In describing my invention in detail, reference will be had to the accompanying drawings wherein like characters denote like or corresponding parts throughout the several views, and in which:—

20 Figure 1 is a view of the track member for the central support.

Figure 2 is a sectional view through the track member and showing the central supporting member thereon.

25 As is well known, a central supporting member 1 having rolls 2 thereon, is used for supporting the central portion of an awning roll, such as shown at A in Figure 2, and in due course of time these rolls will wear 30 through the awning sheet and form holes therein long before the rest of the awning sheet is worn out.

It is the object of my invention to provide 35 means whereby the member 1 can have its position changed so as to bring the rolls against other portions of the awning sheet and thus distribute the wear so that the sheet will have a long life.

In carrying out my invention, I provide a support for a track member upon which 40 the member 1 is slidably mounted. Figures 1 and 2 show this track member as consisting of a substantially channel-shaped plate 1' having a flange 2 at its upper end and a plate 3 fastened to the plate 1' by the bolts 4 and having a hook-shaped flange 5 at its 45 upper end which, with the flange 2, forms a guideway for a block 6 which carries a bolt 7 passing through a hole in the member 1 and fastened to the member by the nut 8. 50 The member 1 is provided with a part 9 which engages the bottom flange of the plate 1'. Thus by loosening the nut 8, the member 1 with its rolls can be adjusted to a new 55 position so as to place the wear of the rolls on a new part of the canvas sheet.

It is thought from the foregoing description that the advantages and novel features of my invention will be readily apparent.

I desire it to be understood that I may 60 make changes in the construction and in the combination and arrangement of the several parts, provided that such changes fall within the scope of the appended claim.

What I claim is:—

Awning supporting means comprising a track member having a guideway at its upper part and a flange at its lower part, a block sliding in the guideway, a bolt carried by the block, a bracket connected with the bolt and having a part engaging the lower flange and rollers for supporting an awning carried by the bracket.

In testimony whereof I affix my signature.

GEORGE M. SCHMIDT.
